SWINGING SPOUT FOR SINTERING MACHINES

Martin L. Cover, Allen Park, Mich., assignor to National Steel Corporation, a corporation of Delaware

Application June 20, 1944, Serial No. 541,251

16 Claims. (Cl. 193—2)

1
This invention relates to sintering machines of the traveling-grate type and, in particular, to a swinging spout for distributing the material to be sintered in the form of a bed on the grate.

Swinging spouts of various types have been used heretofore for delivering granular material to the traveling grate of a sintering machine. Certain difficulties have arisen, however, in the operation of such apparatus. While the use of a leveling or strike-off plate is conventional in sintering machines for determining the level of the top of the bed, there is a noticeable lack of uniformity in the density or degree of compactness of the bed resulting from the non-uniform discharge of material by the swinging spout. This lack of uniformity in the compactness of the bed is objectionable because it results in uneven burning of the combustion material. Some of the sinterable particles are accordingly over fired and some are not fired sufficiently.

Sintering-machine spouts as used heretofore have usually been provided with a forwardly sloping bottom or deflector plate adapted to discharge the material against the leveling plate. Because of the impact of the sintering material against the deflector plate and the abrasive character of the material, it has been necessary to replace the spouts because of the wearing out of the plate, even though the other portions of the spout have a much longer useful life. This difficulty in maintaining the spout in operative condition represents an addition to the operating cost and necessitates shutting down the machine for replacement of the spout.

A further difficulty which has been experienced is the clogging of the spout which results from the fact that the fines to be sintered are mixed with a certain amount of water to make them cohesive sufficiently to prevent them from scattering as dust in the air. The material fed through the spout is thus somewhat sticky and exhibits a marked tendency to collect on the walls of the spout and thereby impede the flow of material therethrough. Because of this condition, it is frequently necessary to stop the machine and clean out the spout manually. This increases the operating cost both because of the manual labor involved and, what is more serious, the interruption in the production of sintered material.

I have invented a novel feeding mechanism for delivering material to the grate of a sintering machine, including a swinging spout capable of delivering material more uniformly than the spouts known heretofore, and provided with means for preventing the material passing

2
through the spout from adhering to the walls thereof. In a preferred embodiment, the spout comprises a depending elongated box, generally rectangular in section, pivotally mounted for swinging movement about an axis through its upper end. The box preferably has front, side and rear walls and a deflector plate extending between the side walls and inclined downwardly from the rear toward the front wall. The front and rear walls terminate short of the deflector plate and the side walls have cut-outs adjacent the deflector plate permitting discharge of material principally from the sides of the box at its lower end. The deflector plate is removable, being disposed in a supporting frame, and may thus be replaced when worn out without necessitating the replacement of the entire spout. Chains suspended in the spout swing over the front wall and deflector plate and have slight longitudinal movement relative thereto, thus dislodging material which might tend to accumulate on those surfaces.

Further novel features and advantages of the spout of my invention will become apparent during the following detailed description which refers to the accompanying drawings illustrating the preferred embodiment. In the drawings,

30 Figure 1 is a transverse section through a sintering machine showing the swinging spout of my invention in rear elevation;

Figure 2 is a partial section taken along the plane of line II—II of Figure 1; and,

Figure 3 is a partial front elevation of the spout.

35 Referring in detail to the drawings, pallets 10 are pushed along suitable guide rails (not shown) below a charging spout 11 and a burner 12 before entering the usual combustion chamber wherein the bed of material 18, deposited on the pallets 40 which form a traveling grate, is subjected to combustion under a down draft after ignition by the burner. Angle bars 14 extending along above the sides of the pallets form continuations of the latter.

45 The spout 11 comprises a front wall 15, side walls 16 and a rear wall 17 forming an elongated structure which is generally box like. The spout is mounted for oscillation transversely of the grate, as indicated in chain lines in Figure 1, being supported on pivot pins 18 passing through the front and rear walls and secured to the walls of a chute 19. The chute extends downwardly from a hopper (not shown) or other source of the granular material to be sintered.

The rear wall 17 terminates short of the lower

3

end of the spout. The side walls have rearward extensions or wings 20 adjacent their lower ends. Horizontally and vertically spaced supporting bars 21 and 22 extend between the side walls adjacent the upper and lower edges of the wings 20, respectively. The bars 21 and 22 are connected by bracing bars 23 welded thereto. The bars 21, 22 and 23 form a frame adapted slidably to support a deflector plate 24. The plate 24 has a bar 25 welded thereto adjacent its upper edge, adapted to engage the upper edges of the bars 23 to suspend the plate in a predetermined position. The plate 24 covers the entire area between the side walls.

The lower edge of the plate 24 is substantially in line with the plane of the front wall 15 which terminates a short distance thereabove. The side walls 16 have cut-outs 26 therein adjacent the lower edges of the front wall and the deflector plate. A curtain 27 in the form of a piece of sheet metal of suitable thickness depends from supporting hooks 28 welded to the rear wall 17. The curtain is welded to a supporting bar 29 which engages the hooks. A link 30 pivoted to the rear wall 17 at 31 is driven by any suitable crank mechanism for oscillating the spout through the desired angle.

Material delivered to the spout 11 from the chute 19 falls downwardly therethrough, strikes the deflector plate 24 and is discharged through the cut-outs 26 toward each side of the spout and, to a variable extent, between the lower edges of the front wall 15 and the plate 24. A leveling plate 32 extends between the angle bars 14, being inclined downwardly and contra to the direction of travel of the pallets. The plate 32 is pivoted on arms 33 secured to a shaft 34. The shaft is journaled in bearings 35 mounted on a cross beam 36. The beam is secured to supporting posts 37 extending upwardly from the frame of the sintering machine (not shown). Side plates or wings 38 extend rearwardly from the plate 32. Adjusting bars 39 having toothed lower edges adapted to engage bolts 40 extending through pairs of spaced posts 41, are pivoted to the wings 38. By means of these bars the plate 32 may be swung about the ends of the arms 33 to give it the desired inclination. The shaft 34 may be turned by any convenient means to vary the level of the lower edge of the plate 32. The posts 41 are secured to a deck plate 42 carried partly on an angle bar 43 extending between the bars 14.

The plate 32 is preferably adjusted so that the lower edge of the plate 24 is substantially in contact therewith when the spout is in central or vertical position. The clearance between the plate 24 and the plate 32 obviously increases somewhat as the spout swings to either side of its central position. The lower edge of the plate 24 is provided with a raised rib 24a which, in the illustrated embodiment, is in the form of a bar welded to the plate. The bar stiffens the lower edge of the plate, serves as a wear piece in case it comes in contact with the plate 32, and also limits the flow of sinterable material directly forward from the plate 24. When the spout is in central position the bar substantially closes the clearance between the plate 24 and the plate 32. As the spout moves to one side or the other, the material tends to flow out through the side openings provided by the cut-outs 26 instead of directly forward from the lower edge or left of the plate 24.

In order to prevent clogging of the spout, I

provide chains 44 suspended from any convenient means such as frame members 45 at points spaced from the pivotal axis of the spout. The chains hang down inside the spout on each side adjacent the front wall, as clearly shown in Figure 2. As the spout swings from its center position to either side, the portions of the chains depending inside the spout swing across the inner face of the front wall, as indicated by chain lines in Figure 1, thereby sweeping the wall and dislodging any material which might tend to adhere thereto. In addition, the chains 44, because they are suspended from points spaced from the pivot pins 18, have a slight sliding movement relative to the walls of the spout as the latter swings from side to side. This further aids in preventing adherence of material to the interior of the spout.

I also provide chains 46 which may conveniently be suspended from frame members 47. The chains 46 hang down inside the spout and overlie the deflector plate 24, being trained around a crossbar 48 in the form of a length of pipe welded to the wings 20 near their upper edges. The portions of the chains 46 inside the spout sweep across the deflector plate 24 in the manner already explained, as the spout oscillates, thereby dislodging material tending to adhere to the plate.

It will be appreciated that the movement of the extreme lower ends of the chains 44 and 46 relative to the mouth or lower end of the spout will tend to prevent any clogging of material therein. This being the most narrowly constricted portion of the spout, is the place where clogging is most likely to occur. While the chains will serve to prevent this under normal operating conditions, any clogging which may result from unusual conditions may readily be cleared by inserting a poker through the open rear side of the spout, the curtain being displaced to the extent necessary to permit manipulation of the poker in the mouth of the spout.

It will be apparent from the foregoing description that the charging spout of my invention is characterized by numerous advantages over the spouts used heretofore for loading sinterable material onto traveling grates. The discharge of material from the spout principally from the sides thereof results in a more nearly uniform distribution of material across the width of the grate. The bed of material when struck off to its final height by the leveling plate 32 is thus substantially uniform in density and combustion thereof proceeds at substantially the same rate at all points across the width of the bed. The removability of the deflector plate 24 permits it to be replaced, when worn, with practically no loss of time and without necessitating a shut down of the machine. The cost of replacing the plate 24, obviously, is much less than that of replacing the entire spout or even reconstructing a spout such as those used heretofore by installing a new deflector plate thereon which requires the bodily removal of the spout from the machine. The chains effectively prevent clogging of the spout even when handling very fine material such as fine dust which has to be rather wet to prevent it from flying. The curtain 27 prevents material from bounding out through the open rear side of the spout, yet permits the insertion of a poker or other clearing means in case any clogging should occur.

Because of the foregoing improvements, a sintering machine provided with the spout of my

invention has a daily output of sintered material substantially greater than that of similar machines equipped with the charging spouts known heretofore.

Although I have illustrated and described but a preferred embodiment of my invention, it will be understood that changes in the construction and relation of the elements illustrated may be made without departing from the spirit of the invention or the scope of the appended claims.

I claim:

1. A spout for delivering granular material to a traveling bed, comprising a depending box generally rectangular in section and having front, side and rear walls, said box being pivotally supported for swinging movement transversely above the bed, a deflector plate between said side walls sloping downwardly toward the front wall, said rear wall terminating above said plate, and a curtain depending from said rear wall toward said plate.

2. A spout for delivering granular material to a traveling bed, comprising a depending box generally rectangular in section and having front, side and rear walls, said box being pivotally supported for swinging movement transversely above the bed, and a deflector plate between said side walls sloping downwardly toward the front wall, said rear wall terminating above said plate, said front wall terminating above said plate and said side walls having cut-outs therein adjacent the intersection of said plate with the plane of the front wall.

3. A spout for delivering granular material to a traveling bed, comprising a depending box generally rectangular in section and having front, side and rear walls, said box being pivotally supported for swinging movement transversely above the bed, and a deflector plate between said side walls sloping downwardly toward the front wall, said rear wall terminating above said plate, said front wall terminating above said plate, and a rib extending across the lower edge of said plate and standing out beyond the plane of the upper face thereof.

4. A spout for delivering granular material to a traveling bed, comprising a depending box generally rectangular in section and having front, side and rear walls, said box being pivotally supported for swinging movement transversely above the bed, a deflector plate between said side walls sloping downwardly toward the front wall, said rear wall terminating above said plate thereby leaving an opening affording access to the interior of the spout.

5. The apparatus defined by claim 3 characterized by said rib comprising a bar welded to the deflector plate.

6. A spout for delivering granular material to a traveling bed, comprising a depending box generally rectangular in section and having front, side and rear walls, said box being pivotally supported for swinging movement transversely above the bed, and a plurality of lengths of chain suspended within said spout in spaced relation, adapted to dislodge material adhering to said walls.

7. A spout for delivering granular material to a traveling bed, comprising a depending box generally rectangular in section and having front, side and rear walls, said box being pivotally supported for swinging movement transversely above the bed, a deflector plate between said side walls sloping downwardly toward the front wall, and a length of chain lying on said

deflector plate and free to slide thereacross on swinging movement of the spout.

8. A spout for delivering granular material to a traveling bed, comprising a depending box generally rectangular in section and having front, side and rear walls, said box being pivotally supported for swinging movement transversely above the bed, a deflector plate between said side walls sloping downwardly toward the front wall, and chains suspended in spaced relation adjacent said front wall adapted to dislodge material adhering thereto.

9. A spout for delivering granular material to a traveling bed, comprising a depending box having side and rear walls and a flat front wall, the front wall extending downwardly below the bottom of the rear wall, said box being pivotally supported for swinging movement transversely above the bed, a supporting frame extending between the side walls below the lower edge of said rear wall and sloping downwardly toward the front wall, and a deflector plate slidable in said frame.

10. Apparatus for delivering granular material to a traveling bed, comprising a leveling plate extending across said bed; and a spout pivotally supported for swinging movement transversely above the bed for discharging granular material across said bed, said spout including a flat front wall, a deflector plate inclined downwardly towards said front wall and terminating below said front wall adjacent said leveling plate, and cut-outs in the sides of said spout adjacent the intersection of said plate with the plane of said front wall whereby the granular material is discharged principally from the sides of the spout at its lower end.

11. A spout for delivering granular material to a traveling bed, comprising a depending box generally rectangular in section and having front, side and rear walls, said box being pivotally supported for swinging movement transversely above the bed, and a flexible member suspended from a fixed point above said spout and depending thereinto, said point being so located relative to the spout that oscillation of the box effects relative longitudinal and transverse movement between said member and said front wall, to dislodge material adhering to said wall.

12. A spout for delivering granular material to a traveling bed, comprising a depending box generally rectangular in section and having front, side and rear walls, said box being pivotally supported for swinging movement transversely above the bed, and a length of chain suspended within said spout adapted to dislodge material adhering to said walls, said chain being suspended from a point spaced from the pivotal axis of the spout whereby the chain on oscillation of the spout, has sliding movement therealong and transversely thereof.

13. A spout for delivering granular material to a traveling bed, comprising a depending box having side and rear walls and a flat front wall, said box being pivotally supported for swinging movement transversely above the bed, and a deflector plate removably positioned between said side walls adjacent the lower end of the box, said plate extending the full width of the spout and forwardly substantially to the plane of the front wall, the plate being inclined downwardly and terminating adjacent the lower edge of said front wall so as to leave a forwardly facing discharge opening at the lower end of the spout.

14. A spout for delivering granular material

7 to a traveling bed, comprising a depending box having side and rear walls and a flat front wall, the front wall extending downwardly below the bottom of the rear wall, said box being pivotally supported for swinging movement transversely above the bed, cross-bars extending between said side walls, said bars being spaced apart horizontally and vertically and lying in a plane inclined downwardly toward the front wall, and a deflector plate slideable on said bars.

15. A spout for delivering granular material to a bed, said spout comprising a box having side and rear walls and a flat front wall and being pivotally supported for swinging movement transversely above the bed, a supporting frame positioned adjacent the lower end of the spout and inclined downwardly toward said front wall, and a deflector plate removably carried on said frame, said front wall terminating above the lower end of said plate to form therewith a discharge 20 opening.

16. Apparatus for delivering a continuous flow of granular material to a bed, comprising a de-

pendent, elongated spout, said spout being pivotally supported for swinging movement above the bed, and a flexible member suspended from above said spout and depending therein in engagement with a wall thereof and adapted to move both longitudinally and transversely relative to said wall of the spout on swinging of the spout whereby material adhering thereto is dislodged.
